UNITED STATES PATENT OFFICE.

FRANK REDICK, OF PARKERTON, WYOMING.

PIPE-SUSPENDING DEVICE AND BLOW-OUT PREVENTER FOR OIL-WELL CASING.

Application filed October 3, 1925. Serial No. 60,299.

To all whom it may concern:

Be it known that I, FRANK REDICK, a citizen of the United States, residing at Parkerton, in the county of Converse and State 5 of Wyoming, have invented new and useful Improvements in Pipe-Suspending Devices and Blow-Out Preventers for Oil-Well Casings, of which the following is a specification.

10 My present invention has reference to a new and novel means for hanging or suspending long strings of pipes in oil wells, as well as for controlling the outflow of gas and water which may flow between any two 15 strings of pipes and for preventing blow-outs between the strings of pipes.

A further object is to simplify and improve the construction disclosed by U. S. Letters-Patent, No. 1,523,897, granted me on 20 January 20, 1925.

In the drawings:

Figure 1 is a side elevation of the improvement with parts in section.

25 Figure 2 is a similar view showing one of the bushings elevated above the adjacent bushing, and the nipple connecting one of the strings of pipe raised prior to having the elevated bushing screwed thereon.

30 Figure 3 is a sectional view on the line 3—3 of Figure 1.

Figure 4 is an approximately central transverse sectional view showing all of the pipes suspended and supported in accordance with this invention.

35 Except in certain novel features of construction and important functions performed thereby, my present invention is very similar to the construction disclosed by the U. S. Patent No. 1,523,897, granted me on 40 January 20, 1925. Therefore, features disclosed by my said patent, which are illustrated by my present drawings, will be only briefly referred to.

A crane or derrick carrying chain hooks 45 is employed for engaging the ears of the bushings and for raising and lowering the strings of pipe casing in a manner and for a purpose which will be presently and fully set forth.

50 In Figure 1 of the drawings the A designates a suitable foundation, of cement or other material. Resting on this foundation there is a metal base 1, and resting on the base 1 there is the enlarged outer end or the head 55 2 of a bushing. The bushing is provided with a cylindrical depending body portion

3 that is received through a central opening in the base 1, the foundation being provided with an opening that aligns with the opening in the base.

As disclosed by the drawings any desired number of bushings are employed, one resting on the other and the body portion 3 of the superimposed bushings being received through the head portions of the bushings. 60 Of course, the bushings gradually decrease in cross sectional diameter and all of the bushings have hydraulic packings therebetween to insure both water and gas tight joints. The bushings are substantially similar to those disclosed in my referred to Patent No. 1,523,897, but the said bushings have their heads provided with outstanding ears to be engaged by the hooks on the chains of the derrick, and the inner faces of the 65 said heads of the bushings have continuous grooves for the hydraulic packings. The confronting faces of the bushing heads have ears 4 arranged at angles of approximately 70 90° and through which ears there are passed 75 bolts 5 which are engaged by nuts 6 for compressing the packings between the bushings to prevent high gas pressure from lifting the bushings apart and allowing oil or 80 gass to pass therebetween.

85 Each of the bushings has the bore of its body portion slightly flared inwardly, and threaded, and these threaded bores are designed to have screwed therein special collars 7 which form an important element of 90 the improvement. These collars, however, are not screwed in the bushings until the pipe sections constituting the casings are arranged in the well, as will presently be understood. The bore of each collar is 95 preferably flared outwardly from the center to the ends thereof, and these flared or conical bores, are threaded for the engagement of pipe members 8 that form the upper sections of the well casing, and likewise for threaded engagement with a removable casing section which is in the drawings, indicated by the numeral 9. When the well casings are lowered in the well until the bottom of the well is reached, 100 a casing section 8 is cut the proper length and screwed on the upper joint of the casing proper. It is customary to allow a certain amount of tension on each string of long pipe constituting the casing, as for instance, say 3500 feet of 8 inch casing pipe should have approximately from 16 to 18

inches of stretch before it would lift the bottom joint off the bottom of the hole. It is usually desirable to hang from one-half to two-thirds of the weight of this string on the casing suspending device, which, in this instance, comprises the bushing. Consequently from ten to twelve inches of "stretch" as it is commonly called, is taken on the casing. In other words, the pipe or casing section 8 is cut so that when it is screwed onto the casing pipe already in the hole it will lack from ten to twelve inches of reaching the proper height. In hanging it up, the casing section 8 is cut the right length to allow for the tension. The specially threaded collar 7 is then screwed onto the casing or pipe section 8. This is facilitated by the arrangement of the flared threaded bore and the flared threaded end of the casing 8. A bushing 2 has then passed therethrough the outer pipe or casing section 9. The pipe or casing section 9 is suspended from the derrick which is also operated to elevate the same to raise the casing section 8 to its first mentioned position. The short pipe or casing section 9 is lowered with the casing into the well until the said casing reaches the bottom and the casing section 8 is screwed up tight to the upper joint of the casing proper. Tension is then taken off of the string of casing by raising the short pipe or casing section 9 (see Figure 2). This also raises one of the bushings 2 off of the bushing immediately beneath it. The raised bushing is screwed on the specially threaded collar 7 and is then lowered until it rests on the next bushing. The bolts 5 are then passed through the ears 4 of the adjacent bushings and the nuts 6 are screwed home on the bolts. The short pipe or casing section 9 is unscrewed from the specially threaded collar and this method is repeated until all of the strings of casing are properly arranged in the well. The lower bushing is bolted onto the base, and, of course, the string of casings supported from the said lower bushing are connected thereto and suspended therefrom in a manner as above described.

The construction and advantages of my improvement will, it is thought, be perfect.

ly apparent to those skilled in the art to which such invention relates when the foregoing description is read in connection with the accompanying drawings. I do not, however, desire being restricted to the precise construction herein set forth and may make such changes therefrom as fall within the scope of what I claim.

Having described the invention, I claim:

1. The combination of a base member arranged over a well and interfitting superimposed bushings on the base, and well casings designed to be suspended from the bushings, each of said casings having its outer pipe section cut and threaded, an interiorly and exteriorly threaded special collar screwed on the said casing section, an outer casing section removably screwed in the collar whereby the casing to which the collar is connected may be raised or lowered into the well and also whereby the special collar may be threaded into a bushing, and the last mentioned casing section thereafter removed from the said outer casing section.

2. The combination with a pipe casing let in a well and a base member arranged over and surrounding the casing, of superimposed bushings, resting on the base, each of said bushings including a head and a reduced body which is received in the head of the adjacent bushing, a specially threaded collar designed to be screwed in the bottom of each of said bushings, said special collar being threaded internally and externally, and designed to have screwed therein a casing section which is threadedly connected to the casing in the well, and each of said specially constructed couplings designed to have removably screwed therein a pipe member which is freely movable through the bushing through which it passes, said pipe member providing a means for raising or lowering the connected casing sections and to permit of the specially constructed coupling being screwed into the body of the bushings prior to the arrangement of the said bushing upon the next lower bushings.

In testimony whereof I affix my signature.
FRANK REDICK.
